Des. No. 2,311.

John Taylor,
Design for a Ladies Hood.

Patented May 8, 1866

John Taylor

Witnesses: Wm. H. Smith,
John Parker

Doc. 2311

John Taylor of Philadelphia, B.

Letter patent No. 2311, dated May 3, 1861.

Design for a ladies' hood.

The article referred to in this letter, Patented, anything part of the same
that where it may occur.

Be it known that I, John Taylor, of Philadelphia, State of Pennsylvania, have invented a new and original design for a ladies' hood, and I do hereby declare the same, together with the following explanation of the same, to be a full, clear, and exact description of the said design:

The figure in the drawing represents the front of the hood, the body of which may be made of any suitable knitted or woven fabric.

The front of the hood is on one side provided with a border of fine fabric twisted together a border b, of small characters standing along the lower edge of the hood, and a similar border c, stands the back of the same.

It is to be observed that the design for a ladies' hood is substantially as shown and described.

I, John Taylor, have signed my name to this specification in the presence of witnesses, in witness.

John Taylor

E. T. W. (Signature)
